[57] CLAIM

The ornamental design for a portable internal combustion engine and tools, as shown and described.

DESCRIPTION

FIG. 1 is a left side elevational view of a portable internal combustion engine, showing our new design;
FIG. 2 is a right side elevational view thereof;
FIG. 3 is a top plan view thereof;
FIG. 4 is a bottom view thereof;
FIG. 5 is a rear elevational view thereof; and
FIG. 6 is a front elevational view thereof.
